UNITED STATES PATENT OFFICE.

MEINHARD H. KOTZEBUE, OF TULSA, OKLAHOMA, ASSIGNOR TO EDWARD R. KEMP, OF TULSA, OKLAHOMA.

VAPORIZING-BURNER FOR HYDROCARBON FUELS.

1,393,547.

Specification of Letters Patent. Patented Oct. 11, 1921.

Application filed October 6, 1920. Serial No. 414,966.

To all whom it may concern:

Be it known that I, MEINHARD H. KOTZEBUE, a citizen of the United States, residing at Tulsa, in the county of Tulsa and State of Oklahoma, have invented certain new and useful Improvements in Vaporizing-Burners for Hydrocarbon Fuels; and I do hereby declare the following to be a full, clear, and exact description of the invention, such as will enable others skilled in the art to which it appertains to make and use the same.

The object of the invention is to provide a simple, inexpensive and efficient vaporizing burner in connection with which may be used hydrocarbon fuels of a more or less crude or unrefined form under conditions conducive to economy in the consumption and cost of the fuel together with completeness of combustion; and with these objects in view, the invention consists in a construction and combination of parts of which a preferred embodiment is shown in the drawings, wherein—

Figure 1 is a side view of a burner embodying the invention,

Fig. 2 is a top plan view of the same,

Fig. 3 is a vertical longitudinal section on the plane indicated by the line 3—3 of Fig. 2,

Fig. 4 is a horizontal section on the plane indicated by the line 4—4 of Fig. 3, and

Fig. 5 is a detail section on the plane indicated by the line 5—5 of Fig. 3.

The burner consists essentially of a vaporizing retort 10 in the form of a tubular conductor with which communicates the fuel supply pipe 11 having a suitable controlling valve 12, an annular superheating retort 13 for complete longitudinal traverse by the vaporized fuel from the inlet 14 thereof to the outlet 15, a transverse partition 16 being arranged in said superheating retort to insure the direction of travel indicated by the arrow in Fig. 4, a burner cap 17 in the general form of an inverted cup and constructed for example of refractory material or of suitable metal, a mixing tube 18 disposed in an upright position with its upper or discharge end within the burner cap, and a feed tube 19 extending downwardly from the superheating retort and provided with a gas outlet orifice 20 controlled for example by a needle valve 21.

The vaporizing retort is provided with a filler consisting of a mass of steel wool 22, a mass of gravel 22^a, and a mass of steel

wool 22^b, the gravel being arranged between the masses of steel wool. The retort is inclosed in a jacket or sleeve 23 of asbestos within which is located a heating unit in the form of a resistance coil 23^a in circuit, as for example, by the conductor 24 with a battery 25 or other source of electrical energy, a suitable switch 26 also being included in the circuit.

The feed tube 19 is also inclosed in a jacket or sleeve of asbestos within which is located a heating unit in the form of a resistance coil 27^a which is also included in the same circuit with the heating coil 23^a. These heating coils are employed to effect an initial vaporization of the fuel whereby to permit the burner to be quickly ignited. Within a very short time after igniting the burner, the retorts 10 and 13 will have become heated sufficiently to vaporize the fuel, and when this occurs the switch 26 is opened to break the circuit to the heating units as they need no longer be employed. These heating units provide an excellent means for producing a rapid initial vaporization of the fuel, and they may be conveniently controlled. The asbestos jackets surrounding the heating units cause all the heat generated therein to be spent in the vaporization of the fuel.

The burner cap is arranged within and concentric with the superheating retort and is provided with radial burner slots 17^a through which the mixture of fuel and air or the like combustion supporting agent is discharged to be ignited exteriorly of the cap, the latter having a substantially cylindrical side wall and a centrally depressed or cupped upper wall as indicated at 28. The top of the burner is preferably coned downwardly at its inner side to form a spreader 29 located in axial alignment with the mixing tube 18 which is preferably contracted between its lower and upper ends and is bellied or expanded terminally as shown clearly in Fig. 3, so that while the lower or inlet end thereof serves to provide for the influx of an adequate supply of air to be mixed with the vaporized fuel, the upper end serves to permit of the expansion thereof around the spreading cone 29 to provide for a substantially uniform distribution of the mixing to the periphery of the burner cap.

The superheating retort is supported by suitable standards 30 from a base 31, and

the burner cap and mixing tube are supported by inwardly directed brackets 32 from the upper ends of said standards, as also shown in Fig. 3, the mixing tube having 5 an exterior sleeve 33 provided with a flange 34 upon which the burner cap rests at its lower edge. The sleeve 33 extends to the upper flared edge of the mixing tube and is spaced from the inner surface of the wall 10 of the burner cap to form an annular chamber 34 through which the mixture circulates in finding an outlet to the radial slots in said cap.

It will be seen that the arrangement of 15 the superheating retort in surrounding relation with and in proximity to the burner cap, in a plane between the upper and lower edges thereof, serves to dispose said retort in the zone of the flame due to the combustion 20 of the mixture exteriorly of the burner cap, while the lowering of the temperature of the mixture in the superheating retort in its passage to the burner orifice 20 is prevented by the auxiliary heating apparatus con-

sisting of the electric unit embracing the 25 feed tube 19. The needle valve 21 may be controlled and actuated by a suitable operating lever 36, said valve passing through a suitable stuffing box 37.

Having thus described the invention, what 30 I claim is: —

A liquid fuel burner construction including a frame having standards, brackets extending from the standards, an annular retort mounted by the standards, a burner construction surrounded by the retort and mounted by the brackets, a fuel supply conduit extending from the retort below the burner and having a discharge valve therein, and means mounted by one of the standards 35 to control said valve. 40

In testimony whereof I affix my signature in presence of two witnesses.

MEINHARD H. KOTZEBUE.
